UNITED STATES PATENT OFFICE.

EDWARD DENEGRE, OF CHICAGO, ILLINOIS, ASSIGNOR TO McCORD & COMPANY, OF CHICAGO, ILLINOIS, A CORPORATION OF NEW JERSEY.

AXLE-BOX COVER.

No. 817,753.

Specification of Letters Patent.

Patented April 17, 1906.

Application filed December 5, 1903. Serial No. 183,847.

To all whom it may concern:

Be it known that I, EDWARD DENEGRE, a citizen of the United States, residing at Chicago, in the county of Cook and State of Illinois, have invented certain new and useful Improvements in Axle-Box Covers; and I do hereby declare the following to be a full, clear, and exact description of the invention, such as will enable others skilled in the art to which it appertains to make and use the same.

My present invention relates to car-axle-box lids, and has for its object to improve the same in the several particulars hereinafter noted.

The invention consists of the novel devices and combinations of devices hereinafter described, and defined in the claims.

The leading feature of my invention is directed to the provision of a lid which is universally adjustable—that is, may adapt itself to the mouth-opening of the box—and which, furthermore, when closed will interlock with the box. Both of the above features are extremely desirable, and they have not hitherto, so far as I am aware, been incorporated or combined in the same device.

The invention contemplates various other features of improvement, all of which are attained in the improved form of lid and lid-support illustrated in the drawings and hereinafter specifically described.

In the drawings like characters indicate like parts throughout the several views.

Figure 1 is a view in front elevation, showing a car-axle box having applied thereto a lid designed in accordance with my invention. Fig. 2 is a vertical section on the line $x^2 x^2$ of Fig. 1, some parts of the axle being broken away. Fig. 3 is a detail in horizontal section on the line $x^3 x^3$ of Fig. 2. Fig. 4 is a detail in horizontal section on the line $x^4 x^4$ of Fig. 2, some parts being broken away. Figs. 5 and 6 are sections taken on the line $x^5 x^6$ of Fig. 2 looking toward the left at the former and toward the right at the latter. Fig. 7 shows the lid-carrying arm in detail sectioned on the same line as in Fig. 2; and Fig. 8 is a section corresponding to Fig. 2, but with the lid shown in an open position by full lines and in an unlatched but closed position by dotted lines.

The numeral 1 indicates the axle-box, which at its upper portion and adjacent to its

lid-opening 2 is formed with a heavy hinge-lug 3, having a projecting fulcrum edge 4. At the lower portion of the opening 2 the axle-box 1 is formed with an internal lock-flange for a purpose which will presently appear, and it may also be here noted that the base of the lug 3 is cut away just above the opening 2 to form a transverse channel or seat 6 for a purpose which will also presently appear. The lid 7 is carried at the free end of an arm 8, which arm is preferably of shell-like form and is hinged to the box-lug 3 by a hinge-bolt 9, passed through the said lug and through the lug-embracing side flanges of the said arm. At its free end the lever-arm 8 is formed with a transverse web 10, that is set inward with respect to the outer web of the arm. The web 10 is formed with an elongated slot 11 and with an oblique or beveled cam-surface 12 for co-operation with the lid, as will presently be noted. The outer web of the arm 8 is terminated short of its free end in a transverse spring bearing or rib 13, and at its extreme free end it is formed with an opposing spring-bearing, shown as afforded by a pair of laterally-spaced bearing-lugs 14. A flat leaf-spring 15 reacts against the spring-bearings 13 and 14 of the arm 8 and at its other end engages in the closed position of the lug with the fulcrum edge 4 of the hinge-lug 3 and in the open position of the lid with the flattened upper surface of the said lug.

The lid 7 at its central portion is formed with an outwardly-projecting hub 16 and with an oblique beveled cam-surface 17. The hub portion 16 works loosely through the elongated slot 11 of the lever 8 and is permanently secured to the web 10 of said lever by a rivet 18 and a washer 19. The hub 16 is long enough to permit the lid to move laterally with respect to the web 10, and the elongation of the slot 11 permits the lid to move longitudinally of the lever—that is, in a vertical direction—when the said lever is turned downward. At its lower portion the lid 7 is formed with a latch or lock lug 20, which is adapted to interlock with the lock-flange 5 of the box, and thus lock the lid in a closed position, as shown in Fig. 2. Furthermore, the under surface of the lug 20 is beveled inward and upward, so that when the lid is closed under the action of the spring 15 the said lug will engage with the lock-flange 5, force the lid slightly upward on the lever,

and after passing inward beyond the said flange will permit the lid to again drop under the action of gravity, and thus lock the lid in its closed position. It is important to here 5 note that when the lid is closed, as above described, the beveled cam-surfaces 12 and 17 of the arm 8 and lid 7, respectively, co-operate under the pressure of the spring 15 to force the lid downward, and thus assist 10 gravity in automatically locking the lid in a closed position. Furthermore, the said cam-surfaces under the pressure from the spring tend to keep the lid forced downward and its lock-lug 20 interlocked with the lock-flange 15. At its extreme lower edge the lid is formed with a depending finger-piece 21, which may be conveniently taken hold of to unlock and raise the lid. As is obvious, to unlock the lid it is necessary to first force the same slightly upward, so as to raise its lock-lug 20 above the lock-flange 5, as shown by dotted lines in Fig. 8. This being done, the lid may of course be readily turned upward into the position shown by full lines in Fig. 25. As shown, the lid is formed at its upper edge with an inturned flange 22, which when the lid is closed and locked bears against the upper portion of the box and affords a dust-proof joint between the lid and the box. The 30 groove or seat 6 in the hinge-lug 3 affords clearance for the flange 22 when the lid is slid upward, as shown by dotted lines in Fig. 8, to unlock the lid preparatory to opening the same.

35 As is evident, with the lid loosely connected at its central portion to the free end of the lid-carrying arm 8 the said lid is capable of a limited universal movement to adapt itself to the face of the box, surrounding its opening 2. 40 The lips 23 on the arm 8 embrace the side of the projecting lid portion 17 and hold the lid from rotating on the said arm.

Both the lid and its carrying-lever 8 are preferably formed from malleable iron. If 45 both were cast together, they would warp, and it would be impossible to so mount them as to always tightly close the opening of the box.

I believe I am the first to provide a lid of 50 the above general character which is mounted with freedom for movements to adapt

itself to the face of the box-opening and which lid will interlock with the box when closed. Hence it will be understood that the device described above is capable of modification within the scope of my invention as herein set forth and claimed. 55

What I claim, and desire to secure by Letters Patent of the United States, is as follows: 60

1. The combination with a journal-box, of a lid having means for interlocking with the box, a lid-supporting lever pivoted to the box, and joint devices connecting the lid and the lever, with freedom for a limited sliding motion in respect to each other, whereby the lid may be made to interlock with the box in its closed position, substantially as described. 65

2. The combination with a journal-box, of a lid having a lock-lug for engagement with the box, a lid-supporting lever pivoted to the box, joint devices connecting said lid and lever, with freedom for a limited sliding motion of the lid in respect to said lever, and a spring reacting between the box, the lever and said lid, and operative to force the lid lengthwise of the lever in the closing movement, whereby the lid will be automatically locked to the box under the action of said spring, substantially as described. 70 75

3. The combination with a journal-box, of a lid having a beveled lock-lug for engagement with the lower lip or flange of the box-mouth, a lid-supporting lever pivoted to the box, joint devices connecting said lid and lever, with freedom for a limited universal movement of the lid in respect to the lever, and permitting a sliding movement lengthwise of the lever greater than the movement in any other direction, and a flat spring reacting between the box, the lever and the lid, and operative automatically to close the lid and to force the same into interlocking engagement with the box, and also operative to hold the lid in its open position, substantially as described. 80 85 90 95

In testimony whereof I affix my signature in presence of two witnesses.

EDWARD DENEGRE.
